SMOKING CHARGE

John L. Brown, Catonsville, Md., assignor of one-half to William W. Varney, Baltimore, Md.

Application February 21, 1929, Serial No. 341,836

7 Claims. (Cl. 131—52)

The object of my invention is the producing of a smoking charge for pipe smokers.

A further object of my invention is the producing of a smoking charge the container of which is substantially neutral and consumable with the charge.

A further object of my invention is the providing of smoking charges attached for packing and selling purposes, but which may be easily detached when desired for consumption.

A further object of my invention is the production of a smoking charge that will substantially feed a smoking receptacle and easily prepared therein for draught to provide combustion.

A further object of my invention is the method of making this new smoking charge that I have invented.

A further object of my invention is an apparatus to accomplish this purpose.

A further object of my invention is the production of a smoking charge which may be carried by a heated and perspiring person without injury to the smoking charge or annoyance to the person, that is, substantially water and heat-proof.

A further object of my invention is the providing of a soft, pliable and substantially hermetically sealed smoking charge.

A further object of my invention is the application of a product of cellulose to a smoking compound.

A further object of my invention is the treating a cellulose substance of viscose with a flavoring for smoking purposes.

A further object of my invention is the forming of the cellulose or a viscose compound into a smoking article.

A further object of my invention is the providing a smoking article or charge as a cigarette shape which is or may be divided at will to give the requisite amount for a single charge.

A further object of my invention is the forming of continuous lengths of smoking charges that may be separated according to the desire of the consumer into individual smoking charges.

With the foregoing and other objects in view, my invention consists of the methods employed, combination and arrangement of systems, apparatus and means as hereinafter specifically provided and described, but it is understood that changes, variations and modifications may be resorted to which come within the scope of the claims hereunto appended.

Pipe smokers have difficulty in filling their pipes owing to the clumsy receptacles from which the

same are filled, the presence of high winds, and from many other causes, resulting in a waste of tobacco. Very often the containers in which the tobacco is carried in the pocket are leaky, causing an annoying and untidy condition in the pocket. Again, pipes as ordinarily filled with tobacco are often difficult to light and keep burning, owing to imperfect ignition initially and imperfect draught within the tobacco. My new smoking charge overcomes all of these difficulties.

In the first place, a condition of cleanliness is obtained by the charge being carried in the pocket, each charge being continuously attached to the other and broken off as desired. This prevents the littering of the consumer's pocket and the charge can be loaded into the smoker's pipe under any weather conditions at any time without loss of tobacco.

The lighting of the charge is easily accomplished by lighting the tip of the smoking charge, when a uniform and continuous combustion is had through the entire mass, the container burning with uniformity transmits the fire to the edges after it has been started in the center. The container being of neutral material, does not affect the flavor unless it is desirable, in which event the container is conditioned, flavored or colored according to the smoker's taste, by soaking in a solution. I have found that a petunia and a casing solution formed by soaking Havana tobacco in water in varying strength can be used. I have used 1 pound of tobacco in 5 gallons of water as a casing compound. This does not dissolve the wrapper, but adheres and forms a desired color and flavor thereof when viscose is used, as described later.

In the drawing of the herein described embodiment of my invention, Figure 2 is a side view in elevation of a section of a continuous portion of my smoking charge twisted up into individual charges; Fig. 1 is a section of my smoking charge before twisting up; Fig. 3 shows a pipe in which one of my individual charges is being prepared for smoking; Fig. 4 is a section view of a mould for moulding or drying the bunch before the same is coated with the viscose, and for use after the coating with the viscose; the mould may be for forming cigars with shaped ends, or may be of the same cross-section at the ends for cigarettes or any other desired configuration.

Similar numerals refer to similar parts throughout the several views.

1 is the coating of viscose. 2 is the smoking charge, such as tobacco. 3 is the top section of the mould which may be jacketed as shown in the

drawing for heating purposes, and 4 is the bottom section of the mould, the tobacco being laid in the bottom section of the mould and the top section jammed down on it which dries it, leaving it in a solid, smooth form for coating. If desired, the 5 coated smoking bunch may be again placed in the bottom mould and the top section pressed thereon curing the container.

To accomplish the above results I can best illustrate my meaning by citing the well-known and familiar means of stuffing sausages, where the meats are forced into a container and the latter is twisted at intervals to provide definitely portioned sausage units. I have discovered that 10 smoking mixtures, such as tobaccos and their apportioned mixtures and flavors, may be fed through a spout and into a container formed out of what is known on the market as viscose, which I will later describe as being very well adapted for 15 this purpose. The viscose being moistened can be shaped and formed into a container and will adhere to itself, forming a continuous tube. This is filled as a sausage skin is filled and at predetermined intervals separated into units as 20 sausage is separated. The aggregate of the units being attached are properly coiled and packed in condition to receive the Government stamps for 25 sale.

I have thus briefly illustrated one method for 30 forming my smoking charge. Another, and a very well-known method for forming my smoking charge, is the making of capsules out of viscose and filling the capsules with apportioned smoking mixtures, either by hand or by any of the 35 familiar capsules filling machines. These capsules may be made by moistening the sheet viscose and forming the same in a male and a female die and cutting, or by any other well-known process of capsule making; or the fluid, or semi-fluid, viscose may be used to make capsules in a 40 manner similar to that used in the manufacture of gelatine capsules by coating a die in fluid, curing the same and then stripping and cutting.

Another very satisfactory method is the making 45 of large diameter cigarettes in the usual way using viscose or a similar wrapper containing similar properties. This form may be made as a continuous product as the cigarettes are before cutting and led off and coiled, an ordinary cigarette machine being used for larger diameters; the cellophane being moistened for working 50 purposes and adhesion upon itself, as set forth in another application, or a paste may be used suitable for viscose, such as a solution thereof, and thus maintaining its intactness under wet 55 conditions. If it is desired to have the smoking charges in sausage-like links, sections of the continuous cigarette may be twisted either by hand or automatically (the object of another application) forming sausage links, as it may be expressed; the moistening of the viscose renders it 60 extremely tough and pliable, and it is comparable with sausage skins.

My smoking charge whether made individually 65 as in a capsule, or in a sausage link and broken therefrom, or broken off or cut from a continuous cigarette formed, is inserted longitudinally into the bowl of a pipe, the same being preferably moistened before inserting, and especially should 70 the ends be moistened where the sausage link type is used. The charge is rammed into the bowl, and the paper being moist becomes very flexible and yieldable, making a tight fit in the bowl. A sharp implement, such as the blade of a 75 pocket knife, a needle, or some other suitable

puncturing implement, is used to puncture both ends of the smoking charge to permit draught. Upon lighting, the cellophane burns slowly circumferentially igniting the charge as it proceeds thus maintaining combustion at the periphery of 5 the charge, a most desirable feature.

The continuous cigarette type, or the sausage-like type, may be coiled or packed in any convenient manner suitable for cutting or breaking apart into individual charges, as desired; whereas, the individual smoking charges, such as the short cigarette or capsule type, may be sold or in proper cartons.

In this case, each smoking charge is detached from the other and may be marked singly with 15 the proper revenue stamp, or in boxes as other smoking mixtures are sold. I do not wish to limit myself, however, to that particular construction of an individual smoking charge, or to any particular material for a smoking charge, or to any 20 particular material for the wrapper thereof.

I have discovered that the product known as 25 viscose is adapted for the wrapper, or container, both for the making of the capsule or the, if I may so express it, sausage product.

I do not wish to be limited, however, to the use 30 of the substance, viscose, which is formed of highly purified cellulose being mercerized with caustic soda and the resulting alkali-cellulose being treated with carbon disulfide to form cellulose xanthate which is dissolved in water and caustic 35 soda to form viscose, thin layers of viscose being coagulated by a solution of mineral salts and the cellulose regenerated by mineral acids; the sheet so obtained being washed, bleached and impregnated with a softener such as glycerine, and then dried; as any suitable cellulose may be used, as I have found cellulose practically a neutral burning substance, by which I mean without taste or flavor by itself.

I have also discovered that viscose prepared 40 from cellulose is a free-burning substance and suitable for smoking products as a wrapping substance, especially for cigarettes, cigars and cheroots.

I have also discovered that when used in a fluid 45 condition bunches of smoking mixtures compacted may be dipped and have formed around the same the cellulose, forming an impervious wrapping means, this eliminating entirely the 50 mechanical operation of sheet material formed previously to wrapping, the container in this case being formed around the bunch as made. The bunch before coating is preferably formed of a moist or conditioned tobacco and then compacted 55 and seasoned or dried to give it rigidity and shape. This is ordinarily done in a heated mold.

In this specification and claims, when I use the term "viscose", I mean an inflammable product 60 prepared from cellulose to form thin layers of viscose coagulated, treated and formed into thin sheets.

Having thus described my invention, what I 65 claim and desire to secure by Letters Patent is:

1. The process of wrapping a smoking bunch to be used in a pipe bowl consisting of forming a bunch when the materials thereof are in a moist condition then pressing said bunch in a heated mold to dry the same, then coating said bunch with a coating solution the major part of which is viscose, then permitting said coating to solidify thereby forming a wrapper for said bunch.

2. The process of casing viscose consisting of coating the surface thereof with a petunia fluid.

3. The process of casing viscose consisting of

coating the surface thereof with a casing fluid consisting of a solution of tobacco.

4. A plurality of smoking charges formed integral separated by a narrowing of the container between the charges whereby by the breaking of the container at the narrowed portion thereof the charges are separated.

5. A plurality of smoking charges contained within a substantially inflammable, neutral and water-proof container formed integral separated by a narrowing of the container between the bunches whereby by the breaking of the container at the narrowed portion thereof the charges are separated.

10 6. A plurality of smoking charges contained

within a viscose container formed integral separated by a narrowing of the container between the bunches, whereby by the breaking of the container at the narrowed portion thereof the charges are separated.

5

7. A smoking charge comprising a container of cellulose xanthate formed into viscose, coagulated, treated and reduced to flexible sheet form, a smoking mixture in one portion of the container, a smoking mixture in another portion of the container, said portions of the container being connected to each other by a twist in the container wrapper intermediate said portions.
